Walter A. Spear, Cincinnati, Ohio, assignor to NuTone,
Inc., Cincinnati, Ohio, a corporation of New York

Application October 3, 1957, Serial No. 47,957

Term of patent 14 years

(Cl. D52—10)

Fig. 1

Fig. 2

Figure 1 is a front elevational view of a built-in fold down bathroom scale, showing my new design.

Figure 2 is a side elevational view thereof.

Figure 3 is a perspective view showing the built-in fold down bathroom scale in opened condition.

The broken line portion in Figure 3 of the drawing indicating wall and floor structure is for illustrative purposes only.

The back and sides not shown are substantially plain.

I claim:

The ornamental design for a built-in fold down bathroom scale, substantially as shown and described.
